UNITED STATES PATENT OFFICE

BEN B. MANASTER, OF CHICAGO, ILLINOIS

GARMENT CONNECTER

Application filed June 4, 1932. Serial No. 615,400.

My invention relates to certain novel improvements in a garment connecter, and has for its principal object the provision of an improved construction of this character which will be highly efficient in use and economical in manufacture.

Among the salient objects of this invention is to provide a connecter of the character hereinafter set forth, which includes a retractile structure capable of being associated with hook or connecting elements of various forms and designs whereby to make the connecter adaptable for universal use, such as, for example, retaining the lower front portion of a shirt within the upper portion of the trousers, or connecting the buckle to one end of a belt, or attaching an end of a suspender to the button of the trousers.

I am aware of the fact that numerous attempts have been made to provide a connecter capable of accomplishing the result hereinbefore stated. With this in mind it is my desire and aim to provide a connecter of such a structure as will accomplish a result not heretofore accomplished by connecters for like purposes, such as, for example, eliminating an undesirable pull on the garment.

It is common knowledge that in the use of connecters of this character there is a distinct noticeable pulling effect between the portions of the wearing apparel connected together by the connecter. Such pulling effect obviously results in discomfort to the wearer, and is a constant reminder of the presence of the connecter. It is the intent to eliminate this undesirable pulling effect. To accomplish this apparently new result I provide a retractile element constructed in a manner such that the extension or extension and retraction is evenly distributed over the entire area of the structure without decreasing the durability and usefulness of the same for the purposes intended. By this uniform distribution of extension or expansion and retraction the retractile structure extends or expands with the slightest degree of pulling exertion, and when relieved from such pulling force uniformly retracts to its normal position. This results

in the substantial absence of the usually noticeable pulling effect between the portions of the wearing apparel.

A still further object of the invention is to provide connecting elements with the retractile structure of such a structure which will not tear or flaw that portion of the wearing apparel to which they are connected such as results where spring clamps with toothed edges are used.

Another object of the invention is the provision of a garment connecter which may be incorporated in a body of non-elastic structure, thereby dispensing with elastic fabric which in a short time loses its elasticity by reason of constant expansion and retraction, and body perspiration.

Other objects will appear hereinafter.

The invention consists in the novel combination and arrangement of parts to be hereinafter described and claimed.

The invention will be best understood by reference to the accompanying drawing, showing the preferred form of construction and in which:

Fig. 1 is a perspective view of the invention showing the same in applied position;

Fig. 2 is a perspective view of the same showing the invention in a position to be placed in applied position;

Fig. 3 is a perspective view of the invention illustrated in Fig. 2;

Fig. 4 is a perspective view of the invention illustrating a slightly modified form over that shown in Fig. 3;

Fig. 5 is a perspective view of the invention illustrating a modified form of construction over that shown in Figs. 3 and 4;

Fig. 6 is a perspective view of the invention showing a modified form of construction over that shown in Figs. 3 to 5 inclusive, and showing the invention associated with a belt structure;

Fig. 7 is a perspective view of the invention illustrated in Fig. 6, and

Fig. 8 is a perspective view of the invention showing a modified form of construction over that illustrated in Figs. 3 to 7 inclusive, and showing the invention associated with an end portion of a suspender or the like.

Referring to the drawing in detail, it will be noted that my connector is preferably formed from a single strand of wire and includes a retractile structure that is indicated by the reference numeral 10 and which is bent or shaped to provide spaced bars 11. These bars are spaced from each other in the form of the invention as shown in Figures 1 to 3 inclusive by means of spring coils or loops 12 which join the adjacent ends of the bars together.

The wire at one end of the retractile structure is bent to provide a garment connecting element in the form of a clamp 13 which comprises bar members 12' and 17, while at the other end, the wire member is bent to provide a garment connecting element in the form of a closed loop 14, the outer end of which is reduced to form what may be termed a hook element 14'. The end bar of the retractile structure adjacent to the clamp 13 is indicated by the reference numeral 15' and formed on one end of the bar 12' and merging into the bar 15' is a lip 15 that extends beyond one side edge of the retractile structure and is curved away from one face thereof, and from the clamp 13, as shown. The bar 17 is formed on the opposite end of the bar 12' and terminates in a curved free end to cooperate with the lip 15 to guide a portion of a garment between the bars 12' and 17, the latter being crimped longitudinally and arranged in parallelism with the bar 12' for cooperation therewith to set up a clamping action against the garment portion as will be apparent upon inspection of Figure 1.

In Figs. 4 and 5 I have illustrated a slightly modified form of construction over that shown in Fig. 3. In Fig. 4 the bars 18 of the retractile structure are arranged in zig-zag formation as shown in the drawing. In Fig. 5 the terminals of the bars 18 are joined together by a single loop 20 instead of a double loop, such as shown in Figs. 3 and 4.

In Fig. 6 the invention is illustrated as serving to connect the buckle 21 to one end of a belt 22. The invention illustrated in Fig. 7 is substantially similar to that illustrated in Fig. 4, with the exception that the clamp 13 is dispensed with and in lieu thereof this end of the wire member is bent to form a closed loop 23' with the outer end thereof formed to provide hook 23 which is adapted for hooked engagement with the cross bar 24 of the buckle 21.

In Fig. 8 the invention is illustrated as being associated with an end of a suspender or the connecting strap of a garter, and to apply the invention for this purpose the clamp 13 is dispensed with and in lieu thereof there is provided a closed loop 25 disposed opposite the closed connecting element or loop 14. By the use of a connector with

a suspender, garter, etc., the said suspender or garter may be made of non-elastic material. In this instance the connector serves the purpose of the elastic material or elastic section which is usually incorporated in suspenders, garters, etc.

As previously indicated, I am aware of the fact that connectors or fasteners, as they may be termed, have heretofore been provided with retractile structures, but these structures have not proven satisfactory especially where the same is made of closely woven wire, as it has been found difficult to make a retractile structure of such character by reason of breakage. This results in the attempt to closely dispose the wire sections together. Again when such a structure is in applied position it is difficult to form the retractile structure so as to permit easy extension and retraction of the hook elements, it appearing that there is a greater resistance in the retractile structure when the same is provided of closely bent wire, round or flat. By providing the loop or coils 12 and 20 the expansion and retraction takes place at the extremities of the bar and these loops are of such design that retraction and expansion takes place with ease, requiring very little pulling pressure to allow the expansion, and yet the connector is durable and will function with the greatest efficiency for the purpose.

The device, as is apparent, is simple in structure, and one which is easily applied in position. By changing the design or shape of the hook or connecting elements the device may have universal application for the purpose.

The connector as a whole may be provided with a covering of fabric or helical wire, such as is partially illustrated at 19, Fig. 8. However, for economical purposes I have found it more desirable to finish the connector by a plating process.

While I have illustrated and described the preferred form of construction for carrying my invention into effect, this is capable of variation and modification, without departing from the spirit of the invention. I, therefore, do not wish to be limited to the precise details of construction set forth, but desire to avail myself of such variations and modifications as come within the scope of the appended claims.

Having thus described my invention what I claim as new and desire to protect by Letters Patent is:

1. A connector formed from a single piece of resilient material and comprising a retractile structure, connecting elements arranged at the ends of the retractile structure, one of said connecting elements being provided with a bar, a crimped bar having one end connected with the first mentioned bar and free at its other end, said crimped bar

cooperating with the first mentioned bar to set up a clamping action and a lip formed with the first mentioned bar and cooperating with the free end of the crimped bar to provide guiding means.

2. A connector formed from a single piece of material and comprising a retractile structure, connecting elements arranged at the ends of the retractile structure, a bar formed with one end of the retractile structure and providing a part of one connecting element, a crimped bar connected at one of its ends to the first mentioned bar and cooperating therewith to set up a clamping action, said crimped bar having a free end, a curved lip formed with the first mentioned bar and cooperating with the curved free end to provide guiding means.

3. A connector formed from a single piece of resilient material and comprising a retractile structure, connecting elements arranged at the ends of the retractile structure, a bar forming a part of one connecting element, a crimped bar connected to the first mentioned bar and cooperating therewith to set up a clamping action, said crimped bar terminating in a curved free end, a lip formed with the first mentioned bar and cooperating with the free end to provide guiding means and said lip extending beyond one side edge of the retractile structure and the free end of the crimped bar.

4. A connector formed from a single piece of resilient material and comprising a retractile structure, connecting elements arranged at the ends of the retractile structure, a closed loop forming one of said connecting elements and comprising enlarged and restricted portions, a bar forming a part of the other connecting element, a crimped bar connected to the first mentioned bar and cooperating therewith to set up a clamping action, said crimped bar terminating in a curved free end, a lip formed with the first mentioned bar and cooperating with the free end to provide guiding means.

5. A connector formed from a single piece of resilient material and comprising a retractile structure, connecting elements arranged at the ends of the retractile structure, a closed loop forming one of said connecting elements and comprising enlarged and restricted portions, a bar forming a part of the other connecting element, a crimped bar connected to the first mentioned bar and cooperating therewith to set up a clamping action, said crimped bar terminating in a curved free end, a lip formed with the first mentioned bar and cooperating with the free end to provide guiding means and said lip extending beyond one side edge of the retractile structure and the free end of the crimped bar for cooperation with the latter.

6. A connector formed from a single piece of resilient material and comprising a re-

tractile structure, connecting elements arranged at the ends of the retractile structure; one of said connecting elements being provided with a bar, a crimped bar having one end connected with the first mentioned bar and free at its other end, and said crimped bar cooperating with the first mentioned bar to set up a clamping action.

In testimony whereof I affix my signature:
